UNITED STATES PATENT OFFICE.

ALANSON P. BRUSH, OF DETROIT, MICHIGAN.

CARBURETING DEVICE FOR INTERNAL-COMBUSTION ENGINES.

SPECIFICATION forming part of Letters Patent No. 730,608, dated June 9, 1903.

Application filed March 7, 1902. Serial No. 97,107. (No model.)

To all whom it may concern:

Be it known that I, ALANSON P. BRUSH, a citizen of the United States, residing at Detroit, county of Wayne, State of Michigan, have invented a certain new and useful Improvement in Carbureting Devices for Internal-Combustion Motors; and I declare the following to be a full, clear, and exact description of the invention, such as will enable others skilled in the art to which it appertains to make and use the same, reference being had to the accompanying drawings, which form a part of this specification.

My invention relates to a novel automatic mixing or carbureting device of superior simplicity, efficiency, and utility; and it consists of the structure hereinafter described and claimed, and illustrated in the accompanying drawings, in which—

Figure 1 is a view in side elevation. Fig. 2 is a view in vertical section. Fig. 3 is a plan view, and Fig. 4 is a detail view in section through the diaphragm and needle-valve.

The purpose of my invention is to provide a device of this character adapted to be employed with internal-combustion motors or engines.

I carry out my invention as follows:

In the drawings, *a* represents a case of any desired construction forming the body of the device, said case with its cap *b* forming an interior passage *d*, constituting a portion of the suction or inlet passage of an internal-combustion motor. Said passage within the case *a* is formed with an enlarged part or chamber *c*, within which is located a baffle-plate or diaphragm *i*. Communicating with the chamber *d* is a fuel or liquid-hydrocarbon supply channel *e*, the communication being controlled by a fuel-valve *f*, seating, as at *g*, beneath the opening or port *h*, through which the passage *e* communicates with the passage *d*. The valve *f* is attached to the baffle-plate *i* and is provided with a valve-stem *m*, loosely engaged at the lower end with the valve. The baffle-plate or diaphragm *i* and the valve are simultaneously movable. The lift of the diaphragm is limited by a stop or other suitable device. As shown, the stop is in the nature of an elastic or yielding stop, formed by a plug *j*, threaded into the cap *b*, said plug provided with a spring *k* at its in-

ner lower end. The said stop is made adjustable, the plug *j* being provided with a handle *l* for adjusting it in the cap *b*. The plug may 55 be held in adjusted position by a lock-nut *n*. The valve-stem passes upward through the stop and is employed to lift the feed-valve to allow a supply of liquid fuel to flow into the inlet-passage *d* in starting the device. The 60 baffle-plate or diaphragm *i* is in no sense a valve and has no seat, but has a free air-opening thereabout between it and the case, as shown. The air-opening thereabout is never closed, even if the stop were screwed 65 down so as to close the fuel-valve. The diaphragm is lifted by the air carried in the passage *d*. A comparatively slight flow of air through the passage *d* is sufficient to lift the diaphragm against the yielding stop, thereby 70 lifting the fuel-valve. Any increase in the flow of air by compressing the spring of the stop increases the opening of the fuel-valve, thereby automatically increasing the amount of fuel admitted as the flow of air increases, 75 or vice versa, thus permitting the speed of the engine to be changed at the will of the operator without varying the quality of the explosive mixture or the use of a governor to maintain a constant speed under varying 80 loads.

The stem of the valve is provided with an offset, as shown at *p*, to prevent the heft of the stem resting on the fuel-valve and adding its weight thereto, inasmuch as it is desirable to have the diaphragm and fuel-valve as light as possible.

The operation of the device will now be understood. The flow of air through the passage *d* strikes against the baffle-plate or diaphragm *i* and is thereby deflected, the flow of air lifting the diaphragm thereby lifting the valve *f*, allowing fuel to enter the channel *d* to be therein mixed with the air in the inlet-pipe. The amount of fuel thus admitted 95 is regulated by the position of the yielding stop, allowing the diaphragm to lift the fuel-valve more or less from its seat.

What I claim as my invention is—

1. In a mixing device the combination of a case formed with a passage, a baffle-plate in said passage, a fuel-supply channel communicating with said passage, a valve attached to the baffle-plate and simultaneously mov-

able therewith to control said communication, and a yielding stop to limit the movement of the baffle-plate and valve, said baffle-plate and valve having a limited movement independent of the yielding stop.

2. In a mixing device the combination of a case formed with a passage, a baffle-plate in said passage, a fuel-supply channel communicating with said passage, and a valve attached to the baffle-plate and simultaneously movable therewith to control said communication, and a yielding stop to limit the movement of the baffle-plate and valve, said valve provided with a stem for lifting the valve independently of the action of the air on the baffle-plate, said stem having a limited movement independent of the movement of the valve.

3. In a mixing device the combination of a case formed with a passage, an unseated baffle-plate in said passage having a free air-opening thereabout, a fuel-supply channel communicating with said passage, and a valve attached to said baffle-plate and movable simultaneously therewith to control said communication, said valve provided with a stem projecting through the case whereby the valve may be lifted independently of the action of the air upon the baffle-plate, said stem loosely engaged with the valve, said valve having a limited movement independent of the movement of the stem.

4. In a mixing device the combination of a case formed with a passage and with a cap, of a movable baffle-plate in said passage, a fuel-supply channel communicating with said

passage, a valve simultaneously movable with said baffle-plate to control said communication, an adjustable plug in said cap, and a spring between the baffle-plate and plug, said valve provided with a stem projecting through said plug, said valve having a limited movement independent of the movement of the baffle-plate and independent of the movement of the stem.

5. In a mixing device the combination of a case provided with a passage forming an interior chamber, a fuel-supply channel communicating with said passage, and a valve attached to the baffle-plate and actuated by the baffle-plate to control said communication, said valve provided with a stem having its weight supported independent of the valve, the baffle-plate having a limited movement independent of the movement of said stem.

6. In a mixing device the combination of a case provided with a passage forming an interior chamber, a baffle-plate in said chamber, a fuel-supply channel communicating with said passage, and a valve attached to and actuated by the baffle-plate to control said communication, said valve provided with a stem loosely engaged at its lower end with the valve, the baffle-plate having a limited movement independent of the movement of the valve-stem.

In testimony whereof I sign this specification in the presence of two witnesses.

ALANSON P. BRUSH.
